UNITED STATES PATENT OFFICE.

ADOLPH F. SCHRAMM, OF COLUMBUS, OHIO.

VEHICLE-SEAT.

1,192,692.

Specification of Letters Patent. Patented July 25, 1916.

Application filed November 6, 1915. Serial No. 60,119.

To all whom it may concern:

Be it known that I, ADOLPH F. SCHRAMM, a citizen of the United States, residing at Columbus, in the county of Franklin and 5 State of Ohio, have invented a certain new and useful Improvement in Vehicle-Seats, of which the following is a specification.

This invention relates more particularly to seats in which the back moves up and 10 down with the seat and its object is to provide an improved and simplified construction in which the back moves down by gravity and up by the rebound of the seat; a further object is a construction in which the 15 back can be readily attached and detached.

The invention is embodied in the example herein shown and described, the features of novelty being particularly pointed out at the close of the description.

20 In the accompanying drawing, Figure 1 is a front view with the upholstery of the back removed. Fig. 2 is a view looking at the right hand end of Fig. 1, parts being in section to show details of construction.

25 In the views 5 designates the rear, 6 the bottom and 7 an arm or end of the main frame. The frame can be curved from the back to the arm. Upon the bottom 6 is removably placed a cushioned seat which includes suitable upholstering springs such as 30 shown at 8, a wired edge 9 and suitable covering 10.

Upon the rear portion 5 of the main frame are secured plates 11 provided with slots 35 12 terminating at their lower ends in enlarged circular openings 13.

The back comprises a suitable frame which can be curved if desired to conform to the main frame. The lower strip of the 40 back frame is rather wide and is designated 14, and has added to it a narrower strip 15 so as to form an angle or rabbet to fit upon and engage the wired edge of the seat. The rear portion of the back frame is provided with a metallic strip 16 containing a 45 pair of studs having heads 16^a, said studs being so located that when the back is lowered to or near the bottom 6 of the

main frame they can be inserted or removed from the enlarged opening 13. When the 50 studs have been so inserted the back can be raised to its normal position. The back is held supported in normal position by the seat after that member has been placed in position on the bottom of the main frame. 55 The back frame is, of course, suitably upholstered by means of springs suitably covered.

The opening between the upper edge of the main frame and the back can be covered 60 to prevent the access of dust etc. by means of a flexible piece 17 secured to the sliding back and buttoned or otherwise attached to the back of the main frame. This covering piece 17 should be of ample width to 65 permit the vertical reciprocations of the back.

The arm of the main frame can be upholstered independently of the seat and back, care being taken to do this in such a 70 way as not to permit abrasion of the moving parts with such upholstering.

This construction is particularly useful in motor vehicles and when the seat is occupied by a rider the back rises and falls with 75 the elevation and depression from normal of the seat. The uncomfortable abrasive action of the seat on the back of the rider is thus avoided.

What I claim is—

1. The combination with a main frame including a rear upright portion, of a yielding seat and a back slidingly connected with said rear upright portion to have a rectilinear movement but not connected with 85 the seat and resting by gravity upon the rear edge of the seat.

2. The combination with a main frame including a rear upright portion, of a yielding seat, and a back removably but slidingly 90 connected with said rear frame to have a rectilinear movement but not connected with the seat and resting by gravity upon the rear edge of the seat.

ADOLPH F. SCHRAMM.
